CLAIM

The ornamental design for a mobile phone, as shown and described.

DESCRIPTION

FIG. 1 is front elevational view of the mobile phone, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view thereof;

FIG. 8 is a rear perspective view thereof;

FIG. 9 is a front perspective view of the mobile phone with the front portion shown in a rotated condition;

FIG. 10 is a rear perspective view thereof;

FIG. 11 is a front perspective view thereof; and,

FIG. 12 is a rear perspective view thereof.

The broken line showing of environmental structures is for illustrative purposes only and forms no part of the claimed design.
